UNITED STATES PATENT OFFICE

138,277

DESIGN FOR A COMBINATION AIRCRAFT CANOPY AND WINDSHIELD

Murray Berkow, Flushing Heights, N. Y., assignor
to Republic Aviation Corporation, a corpora-
tion of Delaware

Application January 22, 1944, Serial No. 112,303

Term of patent 14 years

(Cl. D71—1)

To all whom it may concern:

Be it known that I, Murray Berkow, a citizen
of the United States and a resident of Flushing
Heights, New York city, New York, have invented
a certain new, original, and ornamental Design
for Combination Aircraft Canopy and Windshield,
of which the following is a specification, refer-
ence being had to the accompanying drawings,
forming part thereof.

In the drawings,

Fig. 1 is a perspective view of a combination

aircraft canopy and windshield showing my new
design;

Fig. 2 is a front elevational view thereof; and
Fig. 3 is a rear elevational view thereof.

I claim:

The ornamental design for a combination air-
craft canopy and windshield, substantially as
shown.

MURRAY BERKOW.
